ABRAM D. WILT, JR., OF DETROIT, MICHIGAN.

TWIST-DRILL MACHINE.

978,097.

Specification of Letters Patent. Patented Dec. 6, 1910.

Application filed October 29, 1906. Serial No. 341,109.

To all whom it may concern:

Be it known that I, ABRAM D. WILT, Jr., a citizen of the United States of America, residing at Detroit, in the county of Wayne and State of Michigan, have invented certain new and useful Improvements in Twist-Drill Machines, of which the following is a specification, reference being had therein to the accompanying drawings.

10 This invention relates to the manufacture of twist drills or articles of similar characteristics, and has for its objects the obtaining of an automatic machine for converting the bars of raw-stock into practically the finished product, more particularly by means of a gang machine in which various operations are performed at different work stations simultaneously.

With these and incidental objects in view 20 the invention consists in the novel organization of the machine as hereinafter set forth and a preferred form of embodiment of which is illustrated in the accompanying drawings forming part of this specification.

25 In the drawings, Figure 1 is a plan view of the machine; Fig. 2 is a sectional side elevation thereof; Fig. 3 is a cross section on line 3—3, Fig. 2; Fig. 4 is a cross section on line 3—3, Fig. 2, looking in the opposite direction; Fig. 5 is a longitudinal section through the stock feeding mechanism; Fig. 6 is a perspective view of the milling and cutting off mechanism; Fig. 7 is a section on line 7—7, Fig. 4; Fig. 8 is a sectional end 30 elevation of the mechanism illustrated in Fig. 7; Fig. 9 is a section on line 9—9, Fig. 7; Fig. 10 is a section on line 10—10, Fig. 7; Fig. 11 is a sectionalized and enlarged view of parts shown in Fig. 2.

40 In the process of manufacturing twist drills, it has heretofore been proposed to cut the bars of raw-stock into blanks of suitable length. These blanks are then dressed or shaped by proper tools, and subsequently the 45 spiral grooves are cut or milled thereon, the pitch of the spiral being increased and the depth of the groove tapered from the point toward the shank. In my improved machine, these several operations are performed 50 successively on the work, but there are a plurality of work stations so that the different stages of the work progress simultaneously at the different stations. That is, I have provided a tool holder having a plurality of tools, with a blank carrier confront-

ing this tool holder and carrying chucks or devices for holding a plurality of blanks corresponding to the number of tool stations. Means are provided for cutting off the necessary length of blank from the continuous bar or raw-stock and this blank is gripped by its corresponding blank carrier and then the blank carrier is rotated so as to carry this blank to another station where another stage of the work is performed. In 60 this way as all the blank carriers are provided with blanks, a different stage of the work is being simultaneously carried on at each tool station, and then the rotation of the blank carrier advances each blank to its 65 next tool station for its next succeeding operation. Means are also provided for discharging the finished product after all the successive operations have been performed on it. 75

It has heretofore been proposed to have a plurality of work stations whereby a turret head of tools may operate in this manner simultaneously upon a plurality of blanks, with provisions for rotating the blank carrier so as to produce the successive operations on each blank. But in my present machine I have provided devices by which there is a certain correlation between the work performed at one station and the work 80 performed at the succeeding stations. That is, in the making of such articles as twist drills, if the first operation comprises the dressing or shaping of the blank and cutting of the same from the bar of stock, and then the next operation to consist of milling the spiral 85 grooves, the operation of milling the grooves would be one involving considerable length of time as compared with the mere operation of shaping and cutting of the blank. 90

I have economized time in the present machine by dividing up the cutting of the spiral groove into successive stages, the first groove or mill cut being a comparatively shallow cut at one station, which cut is then deepened by a still further cut at the next station, and so on until the proper depth of cut is secured. And in connection with this segregation of the work, I arrange for tapering 100 the grooves at one of the stations and, if desired, one of the stations may also be used for cutting of the clearance in the grooves. It will thus be seen that with a sufficient number of stations for dividing up this work, 105 the machine can operate with great rapidity 110

and turn out a great many drills in a short space of time. It will be noted, however, that in order to accomplish this result it is necessary so to organize the machine as to maintain a certain definite relation between the work performed at certain successive stations. That is, if the mill cutters at one station are to cut the spiral groove to a partial depth, and then the work is to be carried on to the next station where the groove is to be cut slightly deeper, it is necessary to make sure that the tools at this succeeding station will traverse precisely the same spiral path; and so on for the succeeding stations where work is performed upon this same spiral groove.

It is to accomplish the purpose set forth that I have designed my present machine which will enable me to cut blanks from a continuous bar of stock, shape them at one station, and perform the various cuts and operations upon the spiral grooves at succeeding stations, with the final delivery of the finished product. And this may be applied to the production of other articles than twist drills where it is a requisite that there should be the aforesaid relation between the work traced at one station and the work at succeeding stations. With this general description, the specific form of mechanism which I have adopted will now be described.

A is a suitable frame work. B is a revoluble hollow mandrel mounted upon this frame, through which the bars of stock are fed. The feeding mechanism preferably comprises a reciprocatory inner member C, which frictionally engages the stock bar, and carries it forward within the mandrel together with a non-reciprocating chuck D, which clamps the stock and holds it during the return movement of the member C. The chuck D is operated by a sliding collar E on the mandrel through the medium of the bell crank levers E'. These levers actuate the jaw member D' longitudinally in relation to the outer sleeve D², the latter being provided with a tapering shoulder D³ engaging the jaws in clamping the same against the stock bar. The member C is reciprocated through the medium of a lever C' having a bifurcated end engaging the collar C² on the member C.

The first operations performed upon the stock are the dressing to proper size and the cutting off of a blank of the proper length. These two operations are preferably performed simultaneously, and during the interval in which the stock is clamped by the chuck D by the following mechanism.

F is a non-revoluble mandrel which is in axial alinement with the hollow mandrel B and is mounted in suitable guides for longitudinal reciprocation. F' is a tool mounted in the mandrel F adapted to take a dressing cut upon the projecting portion of the

stock bar beyond the chuck D during the longitudinal movement of said mandrel F. G is a cutting off tool, preferably a revoluble miller, which is arranged adjacent to the chuck D and is fitted into the stock simultaneously with the inner movement of the mandrel F. The cutter G is shown in Fig. 6, and also in Fig. 2, and is driven by a gear wheel Y', later described, which gear Y' meshes with a small pinion fast on the shaft carrying the cutter G and on the opposite side of its supporting bracket as shown in Fig. 6. The movement of these parts is so timed that before the projecting portion of the stock is severed it is dressed to size 80 by the tool F', and is held by the non-revoluble mandrel F.

The operations just described will produce blanks of the proper length and diameter ready for the cutting of the spiral grooves. 85 The latter operation requires the removal of more stock than in either the cutting off or dressing operations and would therefore require a longer time interval for its accomplishment. I have therefore divided this operation into several steps, each of which may be performed in the time interval required for the dressing and cutting off and which together will complete the spiral grooving of the blank. Furthermore, these 90 several operations are performed while the blank is in engagement with a single work holder mounted on an intermittently moving carrier.

As illustrated, H is a revoluble head, or carrier, mounted in the frame, and carrying a series of work holders I, which successively receive the blanks from the non-revoluble mandrel F, and present them in rotation to the groove forming instrumentalities. 100 The carrier H is provided with means for both intermittently revolving it and also for reciprocating it in a direction parallel to the axis of rotation. As shown, the head H is mounted on a shaft H', which is feathered 105 within a sleeve H² revolvably mounted in bearings H³ in the frame. H⁴ is a lever for actuating the shaft longitudinally. H⁵ is a star wheel on the sleeve H² which is intermittently actuated through a partial rotation by a lug or roll H⁶ on a continuously 110 rotating head H'. This star wheel H⁵ is of the ordinary Geneva locking wheel style, having the operating notches with intervening locking surfaces as clearly 115 shown in Fig. 3. The aforesaid roller H⁶, carried by the revolving head H', engages the successive notches of the Geneva star wheel H⁵ to rotate the head H, and for locking the head during the period of rest of 120 the carrier H, the revolving head H' is provided with the projecting flange shown in Fig. 3 which conforms to and engages the said locking surfaces of the star wheel H⁵ and one portion of this flange being broken 125 130

away in the vicinity of the roller H^6 so as to permit the rotation of the star wheel by the roller H^6 . This is a well known form of device which will be readily understood 5 without further description.

The work holders I are in the form of chucks for engaging and clamping the blank while in the non-revolute mandrel F . The jaws of these chucks are operated by a rod I' passing centrally through the work holders, and provided with shoulders for engaging with a coöperating member as will be hereinafter explained. The arrangement is such that when the carrier H is stationary, 10 one of the work holders is in axial alinement with the work in the non-revolute mandrel F , and while in this position the open-jawed chuck is moved forward by the longitudinal movement of the carrier to embrace the projecting end of the blank. The rod I' is then 15 operated to close the jaws of the chuck and clamp the blank, after which the holder is again moved longitudinally in the reverse direction, withdrawing the blank from engagement with the non-revolute mandrel F . All of these movements occur during 20 the interval in which the carrier is locked from rotation by the star wheel actuating mechanism, so that when the rotary movement is again imparted to the carrier the blank will have been disengaged from the mandrel F and firmly clamped by the jaws of the holder. Thus it is free to be carried 25 by the holder through a partial rotation which will bring it into registration with the first of the groove cutting devices.

In cutting the grooves in a drill, it is usual to progressively increase the pitch of the spiral from the point toward the shank 30 of the drill and also to diminish the depth of the groove from point to shank. With the present construction, these grooves are cut by stationary positioned milling cutters and by the combined rotary and longitudinal movement of the work holders in relation thereto. The longitudinal movement of the holder is that which is imparted to it by the carrier H when actuated by the lever H^4 and is the same movement that is employed for engaging a succeeding holder of the series with a dressed and cut off blank 35 in the mandrel F . The rotary movement of the holder is simultaneously imparted to it by the following mechanism, see Figs. 2 and 11.

J is a second head adjacent to the head H and mounted upon the sleeve H^2 intermediate the shaft H and star wheel H^5 , being feathered to each. J' is a carrier on the 40 sleeve H^2 which is in engagement with a lever J^2 by which said sleeve may be longitudinally reciprocated in relation to the shaft H' and the bearing H^8 . The movement of the lever J^2 is determined by a cam J^3 in engagement therewith, while the

movement of the lever H^4 , which controls the reciprocation of the shaft H' and carrier H , is controlled and determined by a cam J^4 . These cams J^3 and J^4 are so proportioned and timed in their rotation that a 70 differential longitudinal movement is imparted to the shaft H' and the sleeve H^2 causing the heads H and J to approach and recede from each other. The head J has mounted thereon in axial alinement with 75 each of the work holders I a projecting pin K having a spiral thread thereon which engages with a complementary internal thread in the holder I . The pitch of this spiral thread is such that a relative movement of 80 the heads J and H will cause the synchronous rotation of all of the holders I in their bearings in the carrier head H , the rotation being in one direction, as the heads J and H approach each other and in the reverse direction as they are separated. Inasmuch, however, as both of the heads H and J are simultaneously moved longitudinally in the same direction, it is evident that the rotation 85 of the holder I can only be produced by 90 their differential movement.

From the description above given, it will be understood that the blanks, while held by the work holders I , will be longitudinally reciprocated in relation to the stationary 95 milling cutters, which will operate thereon to cut the grooves. Furthermore, the rotary movement of the holders, caused by the differential longitudinal movement of the head J , will affect the cutting of the spiral grooves 100 in the blank, the pitch of the spiral being determined by the differential. Thus, to progressively increase the pitch of the groove as is desired, it is only necessary to progressively accelerate the movement of 105 the head J , which may be accomplished by properly fashioning the cam J^3 , as shown in Fig. 11.

To cut the entire length of spiral groove in the time interval in which the dressing 110 and cutting off of the blank is effected, it is impossible to cut the full depth of groove in a single operation. I have therefore arranged a plurality of milling cutters at the several station points of the holders in the 115 intermittent movement of the carrier each succeeding cutter deepening the groove until the required depth is obtained. As illustrated, the cutters are arranged at three different points, and, as two opposite grooves are to be cut in the blank, a pair of opposed millers is arranged at each station. These millers L and L' are mounted upon shafts L^2 and L^3 extending at opposite angles to the axis of the blank. These shafts are 120 driven through a suitable gear train, L^4 , which imparts to the millers the desired speed of rotation. The work is guided, while operated upon by the millers, by passing into engagement with a hollow mandrel 125 130

M which preferably is of a size to closely fit the blank and hold it concentric with its axis of rotation during the cutting operation. Thus, during the forward movement 5 of the carrier head H, blanks will be engaged with the mandrel M at each of the station points, and will be simultaneously advanced longitudinally and rotated to produce the spiral groove. During the return 10 movement of the head H a corresponding reverse rotary and longitudinal movement is given to the blanks, which permits the millers to retrace the grooves cut in the forward movement. To avoid possibility of the 15 blanks sticking in the hollow mandrel, due to the bur raised by the cutting operation, I preferably provide means for expanding the diameter of the mandrel during the return movement of the blank. To this end, 20 each of the mandrels M is longitudinally slotted at M' see Figs. 8, 9 and 10, and the two sections on opposite sides of the slot are provided with ears M² having right and left threaded apertures engaging corresponding threads upon a shank M³. This 25 shank has mounted thereon a pinion M⁴ which engages with an internal segmental gear wheel M⁵, the arrangement being such that during the rotation of said gear wheel 30 the segment will engage with the pinion, and cause the rotation of the shank M³ so as to spread the ears M² and expand the mandrel M. A second internal segmental gear wheel M⁶ is arranged upon the shaft of the 35 gear wheel M⁵, but with the gear segment located at a diametrically opposite point. This segmental gear wheel M⁶ engages with a pinion M⁷ on the shank M³ after a half revolution of the wheels M⁵ and M⁶, and 40 causes the reverse movement of said shank and consequent contraction in the diameter of the mandrel M.

As has been stated, the grooves cut in the 45 drill diminish in depth toward the shank. This taper may be produced in each of the cuts used in forming the grooves, but, for simplicity, I preferably form straight cuts, or cuts of uniform depth in the first two operations and the tapering cut in the final 50 operation. To produce this taper, the millers L and L' are gradually separated during the progress of the work, which may be accomplished by the following mechanism, see Figs. 7, 8, 9 and 10. N and N' are bearings 55 for the millers' shafts L² and L³, which are arranged to slide in guides O and O'. P and P' are threaded shanks engaging corresponding threaded apertures in said bearings and having mounted thereon the pinions Q and Q' which engage opposite sides of a double rack bar R. This rack bar is 60 actuated by an arm S which in turn is mounted for actuation by the reciprocation of the carrier head H. This arm S is also 65 shown in Fig. 2 extending upward from the

left hand end of the horizontal shaft forming the extension of the shaft H', which shaft projects into bearings as shown broken away in said figure so as to permit horizontal reciprocation of the entire shaft for the purpose of moving the carrier H laterally as 70 described. By means of this mechanism, the forward movement of the carrier H will cause the arm S and rack bar R to rotate the pinions Q and Q', and the threaded shanks P and P', which movement will cause the sliding movement of the bearings N and N' in their guides O and O', so as to 75 separate the millers from each other, and gradually to withdraw them from the work. 80 As the amount of movement is not great, the shafts L² and L³ are permitted to tilt in their stationary bearings without interfering with the drive connection. As shown in 85 Figs. 7 and 9, the aforesaid arm S has a brush attached thereto which extends into the inner bore of the mandrel M so that upon the reciprocation of the arm S, in the manner previously described, the brush moves in and out of the mandrel to keep it 90 clear from any possible remnants of cuttings.

The final operation performed on the work is the cutting away of the stock to form the desired "clearance" for the drill. This operation is performed at another station point and preferably by millers suitably arranged to take the required cut. As this clearance cut exactly follows the spiral 95 of the groove, it is evident that it may be produced by millers in stationary bearings. 100

The various parts of the mechanism which have been described are all driven in timed relation to each other by a suitable common driving mechanism, such as the main drive shaft T, and counter shafts U and V. The wheel H' and the cam J³ are mounted upon the main shaft T and the cam J⁴ on the shaft V. Upon the shaft U are mounted the cams U', U² and U³. The cam U' actuates a lever U⁴, which reciprocates the mandrel 105 F, as has been described. The cam U² actuates the sliding carrier E for actuating the chuck D, and the cam U³ operates the lever C' for reciprocating the sleeve C. 110

For operating the chuck of the work 115 holders I, the actuating rods I' are passed centrally through the threaded pins K, and are provided with heads I² which are engaged by the member J when separated from the carrier H. This will cause the drawing rearwardly of the rods I' and the clamping 120 of the chucks. The chucks are opened at the final station point for completing the cycle of the operations by the striking 125 against a stationary stop W. This, as shown, is in the form of a pivoted arm secured to the frame and held in normal position by a spring W'. As shown in Fig. 2, each of the said actuating rods I' extends 130 through its spirally threaded pin K and at

its left end carries the movable jaws of the chuck or work holder. The inner ends of these two jaws are provided with rollers, as clearly shown in Fig. 2, which rollers engage inclined portions of the adjacent body of the chuck holder so that when the rod I' is pulled to the right the rollers will ride up on the inclines and carry the opposite ends of the jaws together so as to clamp the work. And when the rod I' is moved in the opposite direction, the rollers retreat from the inclined portions and the springs which are shown as bearing upon said rollers cause the opposite ends of the jaws to open and release the work. This opening of the jaws by the forcing of the rod I' to the left in Fig. 2 is produced by the striking of the head I^2 against the stop W as above stated. The upper portion of this stop W is sufficiently rounded to permit the head I^2 to ride up over the stop W when the carrier H is rotated to bring this particular chuck or work holder into position. This depresses the stop W against its spring W' at this stage of the movement, but when the carrier H moves forward, the rod I' goes forward with it and allows the stop W to spring up into place so that upon the retraction of the carrier H the head I^2 then strikes the side of the stop W and forces the rod I' to the left, thus releasing the jaws of the chuck or work holder and dropping the finished product into any suitable receptacle therefor, such as shown in Fig. 2 attached to the arm S and resting on the shaft H' and reciprocating back and forth with the arm S .

In the complete operation of the machine, the bars of stock are fed into the hollow mandrel B and are then automatically fed by the operation of the reciprocatory sleeve C and chuck D to successively project blank lengths beyond the end of the chuck. At the same time, rotary movement is given to the chuck through a gear train Y , and the cut off miller G is driven through a gear train Y' . The miller G is fed inward by the movement of a lever connection Z controlled by cam Z' upon the shaft U and the mandrel F is fed over the projecting stock by the cam U' and lever U^4 . This will affect the dressing down and the cutting off, as has been previously described, and at the completion of the operation the chuck of the registering holder I will be engaged with the end of the blank projecting through the end of the hollow mandrel F whereby said blank may be withdrawn upon the outward movement of the carrier. The operation of succeeding cutters has been fully described, and it will be understood that each reciprocation of the carrier head H will affect an operation on each of the blanks, and that one drill is completed and disengaged from its chuck. The disengagement is effected by the striking of

the end of the rod I' against the stop W , which first opens the jaws of the chuck and then knocks the shank of the drill from engagement therewith. All of these operations are performed automatically and it is only necessary for the workmen to feed new stock bars into the hollow mandrel B as required. 70

For changing the form of the spiral groove cut in the drills, it is only necessary to change the relative operation of the heads H and J . This may be accomplished by providing a shifting fulcrum, as, for example, the member J^5 for the levers H^4 and J^2 . By adjusting this fulcrum, the proportion of the levers is changed, and will result in an alteration of the pitch of the spiral. This adjustment is shown in Fig. 2, also in Fig. 11, the bracket or member J^6 being seated in a suitable slideway or guide J^7 on the outer side of the upright framework of the machine. This permits the vertical adjustment of the bracket J^6 so as to adjust the pivotal points of the levers H^4 and J^2 as described. 80 85 90

It will be seen that I have organized the machine so that for those successive stations whereat the spiral groove is retraced and cut successively deeper and deeper, the machine automatically maintains a certain definite relation between the operations performed at such successive stations. The blanks are separated bodily and carried separately from one station to another. Coöoperating with the tool cutters and the blanks carrying devices, is this path-controlling mechanism which insures or causes the tools at the succeeding station to traverse precisely the same spiral path on the work as at the preceding station. That is, this mechanism may in this sense be said to operate correspondingly at each station, and where the word "correspondingly" is used in the claims it is to be understood as having the characteristics above indicated and explained. 100 105 110

What I claim as my invention is:

1. The combination with a work carrier having means for holding a plurality of separate blanks, of a plurality of groove cutters at different stations set for successive cuts upon the work, and mechanism operating correspondingly at each station for presenting the work to cause the successive cutters to trace the same spiral path in relation to the work, and to successively deepen the groove therein. 115 120

2. The combination of means for carrying a plurality of separate blanks to a plurality of stations, groove cutters at different stations set for successive cuts, and mechanism operating simultaneously and correspondingly at each station for presenting the work to cause the successive cutters to trace the same spiral path upon the work presented thereto. 125 130

3. The combination of means for carrying a plurality of separate blanks to a plurality of stations, groove cutters in fixed location at different stations set for successive cuts, and mechanism operating simultaneously and correspondingly at the different stations for feeding the work through the same spiral path in relation to the successive stationary cutters.
- 10 4. The combination of means for periodically advancing a stock bar, means operating while said bar is in fixed position for dressing the end thereof and severing the dressed portion, a work holder for engaging the severed blank, a plurality of groove cutters located at different stations and set for successive cuts, and means for intermittently moving said work holder to the successive stations, and means for moving the work while at said stations to present the work correspondingly to trace the same spiral path in relation to the successive cutters.
- 15 5. The combination with a cutter and a work holder, of means for moving the one in relation to the other, comprising a master spiral and a coöperating sleeve, and means for differentially actuating the same in a direction of the axis of the spiral whereby a spiral trace of the cutter upon the work is produced.
- 20 6. The combination with a cutter and a work holder, of means for producing a spiral trace of said cutter upon said work comprising a master spiral and an engaging member, means for moving said spiral and coöperating member differentially in the direction of their axis, and means for varying the differential.
- 25 7. The combination with a work holder and a cutter, of means for producing a spiral trace of said cutter upon the work comprising a non-rotatable master spiral and a rotatable engaging member, and means for moving said spiral and engaging member differentially in the direction of their axis.
- 30 8. The combination of a revolute member, a non-revolute member having a spiral threaded engagement with said revolute member, means for differentially moving said members axially, and means for varying the differential.
- 35 9. The combination of a rotary work carrier, of a plurality of revolute work holders mounted upon said carrier, a non-revolute member having a spiral threaded engagement with each of said work holders, a member rotating with said work carrier to which all of said non-revolute members are attached, and means for differentially moving said work carrier and co-rotating member in the direction of their axis to cause the simultaneous and correspondingly spiral movement of all of said work holders.
10. The combination with a rotary work carrier, of a plurality of work holders revolubly mounted therein, a shaft upon which said work carrier is mounted, a member feathered upon said shaft to rotate therewith, a non-revolute member having a spiral threaded engagement with each of said revolute work holders, said non-revolute members being secured in said member feathered upon the shaft, and means for actuating the latter member and said shaft differentially in the direction of their axis to produce a correspondingly spiral movement in all said work holders.
- 15 11. In a machine of the character described, the combination with a tool holder having a plurality of tools, and a blank carrier having a plurality of blank holding devices confronting the respective tools; of means for producing intermittent relative rotation between the tool holder and the blank carrier whereby to cause each blank in turn to confront the successive tools; means for operating the tools; reciprocating means for producing relative longitudinal movement of approach and retraction between said tool holder and said blank carrier to effect the working of the tools upon the blanks; and means for producing relative angular rotation between the tools and their respective confronting blanks during the said movement of approach and retraction, whereby to cause the tool to operate spirally upon its blank, said latter means being correlated with the aforesaid reciprocating means to trace the same spiral path at each station.
- 20 12. In a machine of the character described, the combination with a tool holder having a plurality of tools, and a blank carrier having a plurality of blank holding devices confronting the respective tools; of means for producing intermittent relative rotation between the tool holder and the blank carrier whereby to cause each blank in turn to confront the successive tools; means for operating the tools; reciprocating means for producing relative longitudinal movement of approach and retraction between said tool holder and said blank carrier to effect the working of the tools upon the blanks; and means for producing defined revolute movements of said blank holding devices during the working of the tools thereon, said latter means being correlated with the aforesaid reciprocating means to produce corresponding revolute movements of said blank holding devices at each station dependent upon the relative longitudinal distance between the tool carrier and the blank holder.
- 25 13. In a machine of the character described, the combination with a tool holder having a plurality of tools, and a blank carrier having a plurality of blank holding de-

- 5 vices confronting the respective tools; of means for producing intermittent relative rotation between the tool holder and the blank carrier whereby to cause each blank 5 in turn to confront the successive tools; means for operating the tools; reciprocating means for producing relative longitudinal movement of approach and retraction between said tool holder and said blank carrier to effect the working of the tools upon the blanks; means for producing relative angular rotation between the tools and their respective confronting blanks whereby to cause the tool to operate spirally upon its 10 blank, said latter means being correlated with the aforesaid reciprocating means to trace the same spiral path at each station; and means for varying said angular relative movement between the tool and its 15 blank.
14. In a machine of the character described, the combination with a tool holder having a plurality of tools, and a reciprocating blank carrier having a plurality of blank holding devices confronting the respective tools; of means for intermittently rotating said blank carrier to cause each blank in turn to confront the successive tools; means for operating said tools; reciprocating 20 means for moving said blank carrier longitudinally to approach and recede from the tool holder to effect the working of the tools upon the blanks; and means operating correspondingly at each station for producing 25 defined revoluble movement of said blanks in one direction the same definite extent at each station during the forward reciprocation of said blank carrier, and the corresponding extent in reverse direction during 30 the backward reciprocation of the blank carrier whereby to cause the tool to traverse the 35 same path upon said forward and backward reciprocation.
15. In a machine of the character described, the combination with a tool holder, 45 and means for operating said tool holder, of a movable blank carrying frame; a second movable frame coöperating with said blank carrying frame; means for producing differential movement between said frames; and 50 means connected with the blank carriers and operated by said frames whereby to produce a differential extent of revolution of the blank.
16. In a machine of the character de- 55 scribed, the combination with a tool holder having a plurality of tools, and a reciprocating blank carrying frame having a plurality of blank holding devices confronting the respective tools; of means for intermittently rotating said blank carrying frame to cause each blank in turn to confront the successive tools; means for operating the tools; means for moving said blank carrying frame longitudinally to approach and re- 60 cede from said tool holder to effect the working of the tools upon the blanks; a second movable frame coöperating with said blank carrying frame; means for producing differential movement between said two 65 frames; and connections between said blank holding devices and said frames whereby to produce similar differential extents of revolution of said blanks in the various positions to which said blank carrying frame is 70 moved.

In testimony whereof I affix my signature in presence of two witnesses.

ABRAM D. WILT, JR.
